Primary Examiner—Wallace R. Burke*Assistant Examiner*—Marcus Jackson*Attorney, Agent, or Firm*—James D. Welch**[57] CLAIM**

The ornamental design for a combined advertising card holder and mounting support, as shown and described.

DESCRIPTION

FIG. 1 is a front perspective view of a combined advertising card holder and mounting support showing my new design;

FIG. 2 is a rear perspective view thereof; and,
FIG. 3 is a right side elevational view thereof, with the opposite side being a mirror image.
